[57] CLAIM

The ornamental design for a laminator, as shown and
described.

DESCRIPTION

FIG. 1 is a perspective view of the laminator of my
invention;

FIG. 2 is a top plan view of the laminator of FIG. 1;
FIG. 3 is a left side elevational view of the laminator of
FIG. 1;

FIG. 4 is a right side elevational view of the laminator
of FIG. 1;

FIG. 5 is a front elevational view of the laminator of
FIG. 1;

FIG. 6 is a rear elevational view of the laminator of
FIG. 1; and,

FIG. 7 is a bottom plan view of the laminator of this
FIG. 1.

The broken line showing of an electrical cord is for
illustrative purposes only and forms no part of the
claimed design.
